Attorney.

UNITED STATES PATENT OFFICE.

HARTMUT BUDDECKE, OF CHARLOTTENBURG, NEAR BERLIN, GERMANY.

FIRE EXTINGUISHER.

Application filed August 21, 1926, Serial No. 130,699, and in Germany June 4, 1926.

My invention relates to a fire-extinguisher provided with a fuse, preferably of the kind called "quick-match" in mining, transmitting quickly fire to a cartridge by which the extinguishing substance is then thrown automatically upon the burning object whereby the fire is extinguished. The present improved fire extinguisher is so designed as to be adapted for use in connection with a dry or pulverulent extinguishing substance, as well as with a liquid one.

The invention is illustrated diagrammatically and by way of example on the accompanying drawings on which Figure 1 is an axial section through a constructional form intended for use in connection with a dry extinguishing substance, i. e. a pulverulent one, Figure 2 a plan thereof, Figure 3 a view similar to Figure 1, showing a modification intended for use in connection with a liquid extinguishing substance, and Figure 4 a detail of this modification, all as fully described hereinafter.

Referring to Figures 1 and 2, the pulverulent extinguishing substance *d* is enclosed in a metallic casing *a* closed at its bottom by a glass plate *b* affixed to the casing by a screw-cap *c*.

The casing is mounted near the place where a fire may, under circumstances, arise, and in close proximity to this place is located a cap *h* or an equivalent member consisting of an easily inflammable material and being attached to a tube *g* connecting said cap with the casing *a* or, more precisely, with a cartridge located in the head of said casing just over the extinguishing powder *d*. In the tube *g* is enclosed a fuse impregnated with a gun-powder pulp by which the fire can be transmitted practically instantaneously from the burning cap *h* to said cartridge so as to explode the explosive contents thereof. The force of such an explosion taking place in the closed container will cause the glass *b* to become broken and scattered together with the powder *d* over the burning object or fire arising therefrom so as to extinguish the latter.

The explosive powder *j* is enclosed in the cartridge *f* affixed to the casing *a* by a screw-cap *f'* and closed at its inner end by a thin metallic bottom *i*. The fuse extends into the explosive powder, as shown at *k*. More precisely, the cartridge is inserted into an externally threaded socket *e* upon which the

cap *f'* is screwed whereby the cartridge *f* is retained and secured in its place.

Referring now to the modification shown in Figs. 3 and 4, this is intended for use in connection with a liquid extinguishing substance *d'* enclosed in a vessel *m* inserted into the casing *a* and retained therein by a screw-cap *c*. The liquid substance may be tetrachlorocarbon or the like. The bottom *n'* of the vessel *m*, as well as the top plate *n* of the same, are so designed as to be adapted to be destroyed quickly by the explosion of the cartridge. I prefer to use thinner sheet-metal for these parts; besides, the top-plate *n* which is soldered to the inner top rim of the vessel *m* is concave, and the bottom *n'* is provided with a plurality of radial grooves *s*, Fig. 4, diminishing the resistibility of the bottom in such a measure that it gives way immediately after the ignition and explosion of the cartridge.

The fuse carrying tube *g* may have one or more branches *g'* as shown in Figure 3 and the free end of each branch tube is provided with a cap *h'* whereby the cap may be distributed about an object which is liable to catch fire. Bolts *t* are secured to the casing *a* whereby the latter may be attached to a suitable support and the container *m* is provided at one side with a recess *m'* for the reception of the inner heads of the bolts *t*.

I claim:

1. A fire-extinguisher, comprising, in combination, a casing having an open ejecting end, and the walls of which are adapted to resist high internal pressure, an exchangeable vessel in said casing and an extinguishing liquid in said vessel, the top and the bottom of said vessel being so designed as to have a lesser resistance than its circumferential wall; a cartridge located counter to the top of the said vessel; a metallic socket enclosing said cartridge and connecting it with said casing, and a cap nut screwed upon said socket and retaining said cartridge therein; a tube extending forth from said socket and cartridge, a fuse extending from the explosive contents of the cartridge through said tube, and a combustible member closing an opening of the tube and being in contact with said fuse.

2. A fire-extinguisher, comprising, in combination, a casing having an open ejecting end, and the walls of which are adapted to resist high internal pressure, an exchangeable

vessel in said casing, and an extinguishing liquid in said vessel, the top of this latter being formed by a sheet-metal piece which is thinner than the other wall portions of the 5 vessel and soldered thereto; a cartridge located counter to the top of the said vessel; a metallic socket enclosing said cartridge and connecting it with said casing, and a cap nut screwed upon said socket and retaining 10 said cartridge therein; a tube extending forth from said socket and cartridge, a fuse extending from the explosive contents of the cartridge through said tube, and a combustible member closing an opening of the tube 15 and being in contact with said fuse.

3. A fire-extinguisher, comprising, in combination, a casing having an open ejecting end, and the walls of which are adapted to

resist high internal pressure, an exchangeable vessel in said casing, and an extinguishing 20 liquid in said vessel, the bottom of this latter being provided with grooves diminishing the resistance thereof, a cartridge located counter to the top of the said vessel; a metallic socket enclosing said cartridge and connecting it with said casing, and a cap nut 25 screwed upon said socket and retaining said cartridge therein; a tube extending forth from said socket and cartridge, a fuse extending from the explosive contents of the cartridge through said tube, and a combustible member closing an opening of the tube 30 and being in contact with said fuse.

In witness whereof I have hereunto set my hand.

HARTMUT BUDDECKE.
